Primary Examiner — Ricky Pham(74) *Attorney, Agent, or Firm* — Hovey Williams LLP(57) **CLAIM**

The ornamental design for a pet treat forming device, as shown and described.

DESCRIPTION

FIG. 1 is a lower perspective view of a pet treat forming device embodying our design, with a rear hinge element, adjacent hinge mounting structure, lower fastener bosses, forward tabs, and an upper margin of the device being shown in broken lines for illustrative purposes only and forming no part of the claimed design;

FIG. 2 is a front elevation view of the pet treat forming device depicted in FIG. 1, with the upper surface being shown in broken lines for illustrative purposes only and forming no part of the claimed design;

FIG. 3 is a side elevation view of the pet treat forming device depicted in FIGS. 1-2;

FIG. 4 is a rear elevation view of the pet treat forming device depicted in FIGS. 1-3;

FIG. 5 is a side elevation view of the pet treat forming device opposite that depicted in FIG. 3; and,

FIG. 6 is a bottom plan view of the pet treat forming device depicted in FIGS. 1-5.

1 Claim, 4 Drawing Sheets---
